UNITED STATES PATENT OFFICE.

JOHN T. BUNTING, OF CHICAGO, ILLINOIS.

BOILER.

Application filed March 20, 1920. Serial No. 367,509.

This invention relates in general to boilers and has for its object broadly the provision of a boiler for heating purposes and of small size, adapted to operate efficiently with a low fuel consumption.

My invention contemplates the provision of a boiler for hot water or steam heating purposes, wherein the hot gases resulting from the combustion of the coal or other fuel are carried with highly efficient heating effect through a tortuous path from the zone of combustion to the stack outlet.

The embodiment of the invention shown on the drawings discloses an apparatus adapted for use in a hot water heating plant, although it will be manifest when the invention is better understood that the invention may be used in apparatus particularly adapted for the heating by steam or hot air.

Another and highly important object of the invention is the provision of a boiler adapted to entirely consume fuel when soft coal or other ordinarily smoking fuel is employed, with the result that no smoke issues from the stack.

A more specific object of the invention is the provision of a boiler which may be of greatly reduced size for a given heating requirement.

Numerous other objects and advantages of the invention will be apparent as it is better understood from the following description when considered in connection with the accompanying drawings illustrating a preferred embodiment thereof.

Referring to the drawing, Fig. 1 is a front elevation of a boiler embodying my present invention.

Fig. 2 is a rear view thereof.

Fig. 3 is a section taken on line 3-3 of Fig. 1.

Fig. 4 is a section taken substantially on the line 4-4 of Fig. 3.

Fig. 5 is a section taken substantially on the line 5-5 of Fig. 3, and Fig. 6 is a section taken substantially on the line 6-6 of Fig. 3.

The boiler shown on the drawings and embodying my present invention is so constructed and arranged that the heated gases from the fire-box pass first to the rear of the boiler and into one side of a divided chamber, from which they move upwardly and then through fire tubes into a chamber at

the front. From this front chamber they return through other fire tubes into the portion of the chamber at the other side of the partition and from it out to the stack.

As has been stated, the boiler shown on the drawings is designed particularly for the heating of hot water, and a tank or heating boiler is provided above the fire-box so that the heat of the fire plays directly upon the under surface of this boiler. The fire tubes pass through the boiler, and the heated gases of combustion being conveyed back and forth across it give off further heat in their double passage through the water.

A brick structure is provided comprising brick side walls 11, a brick dome or top 12, and a brick back wall 13. The front wall of the boiler comprises a bottom part 14 in which is provided the usual ash pit door 15, carrying a draft door 16. Above this bottom part 14 is arranged the main front wall 17, provided with a fire-box or charging door 18 of any usual or preferred construction. Above the fire-box door there are provided two clean-out doors 20 permitting access to the flues as will be presently described.

Referring to Fig. 3 it will be noted that cross members of T-form 19 and 21 and a front angle member 22 are provided to extend between the internal metal side walls 23 which are positioned against the brick walls 11 in the assembled structure. An abutment 24 is provided within and at the bottom of the back brick wall 13 and upon the rear T-iron 21 are laid bricks 25, forming the bottom of a chamber 26, the purpose of which will be presently described. Upon T's 19 and 21 is built a brick wall 27, providing a flue opening 28 therethrough, this opening being preferably located at one side of the vertical front to back central plane. The grate indicated at 29 rests upon the front angle member 22 and the T 19.

The boiler comprises an outer shell or wall 31 with front and rear end walls 17 and 36, and a crown shield or inner wall 34 with ends 32 and 35. The inner and outer walls 31 and 34 are extended, spaced apart at the sides, and connected at the bottoms of these side portions to form side water jackets 105 continuous with those at the ends which are formed by spacing apart the end walls 17, 32, 35 and 36, and by connecting them by

bottom spacers 32 and 35. Thus the fire box and combustion chamber 26 are completely enclosed at the sides and ends by water jackets, and overhead by the fire tube portion of the boiler. A smoke flue 38 is provided through the narrow water chamber thus formed at the back, this flue being defined by a ring 39 inset in these walls and in registration with suitably provided openings therethrough.

The main back wall of the boiler is spaced from the rear brick wall 13 to provide a flue chamber 41. The flue chamber 41 is divided by a central vertical partition 43 extending from the abutment 24 to well up the side of the boiler. The space provided at one side of such partition is closed at the top by a top wall 42, while the space at the other side is left open and is in communication with the stack outlet, as will be presently described.

A number of flues 44 extend through the boiler from front to back of the furnace, having their ends mounted in the front wall 17 and in the main rear wall 36 at the back of the boiler.

The doors 20 are spaced out from the front wall 17 by a box member 45 which forms a flue chamber 46 at the front. All of the flues 44 open into this front chamber and they are so arranged that half of such flues open into the space at one side of the partition 43 at the back and the other half open into the space at the other side of this partition. The opening 38 is staggered with respect to the opening 28 so that the gases of combustion have to pass into the chamber 26 which is a smoke consuming chamber, and then transversely through this chamber to the opening 38 and into the space at one side of the partition 43 at the back, this space in the present instance being that located at the right-hand side of the boiler. The gases of combustion then pass up through this flue portion and forwardly through the boiler through the right-hand set of tubes 44 into the chamber 46 at the front. From this chamber the heated gases pass back through the other set of flues into the space at the other side of the partition and this space is in free communication with the stack 47.

I introduce outside air above the grate and also into the space 26 therebehind, this air being admitted in the present instance by pipes 48 extending down through the top wall and through the boiler and provided at their lower ends with outlet openings 49. Suitable means indicated at 51 are provided to control the amount of air admitted through the pipes 48. The air admitted by these pipes and mingling with the hot gases results in the completion of the combustion and the oxidation of the usual smoke gases which result from certain fuels as, for example, soft coal.

The circulation of water is in at inlet 52 near the bottom of the boiler at the back and out at 53 in the usual manner.

The clean-out openings 55 are provided at the back to permit cleaning of soot from the divided flue parts at the back, and the usual gauges 56 and safety devices 57 are provided.

Experience has demonstrated that a boiler embodying my present invention will have substantially twice the heating capacity of the boilers ordinarily employed; that is to say, it has been found that the boiler embodying my invention will have substantially the heating power of a present boiler of twice the size.

It will be noted that the outlet 38 from the smoke consuming chamber 26 is materially less in area than the stack and flue space. This results in what might be termed a choking of the gases of combustion within the chamber 26. Air is admitted in suitable fashion as through the pipe 48 at the right of Fig. 3 into this chamber and the flame shooting through the opening 28 ignites and completely burns all combustible products leaving the fire box and passing into this chamber 26. In effect the chamber 26 provides a quiescent air station in the draft system giving ample opportunity for complete smoke consumption.

It will be manifest that all of the metal work of the boiler may be assembled in a single unit at the factory, except of course that the safety devices and grate bars need not be attached, the point being that the brick-work is of a character that permits it to be readily built into and about the boiler after the boiler is constructed and at the time it is being installed into the buildings.

It is thought that the invention and many of its attendant advantages will be understood from the foregoing without further description and it will be manifest that various changes may be made in the form, construction and arrangement of the parts without departing from the spirit and scope of the invention or sacrificing all of its material advantages.

I claim:

1. A boiler comprising an overlying fire tube portion with depending water jacketing sides and ends, a cross partition between the sides with an opening through one side of the partition, the jacketing boiler ends having fire door and smoke flue openings respectively therethrough, the smoke flue opening being on the side of the boiler opposite the opening in the partition to cause a transverse movement of the products of combustion back of the partition and against the rear jacketed end, means forming a partitioned flue box at the rear of the fire tubes, one portion connected with the smoke flue opening and the other portion connected with the smoke stack, and a flue box at the

front of the fire tubes so that the products of combustion are directed through the fire tubes first in one direction and then in the other.

5 2. A boiler having an overlying fire tube portion with depending water jacketing sides and ends, having a front door and a smoke flue at one side of the rear end extending through the jacketing portion, means connecting the smoke flue with the fire tube portion, and a cross partition within the depending portion of the boiler with an opening at the side opposite the smoke flue opening to cause a transverse movement of the hot gases below the fire tube portion.

10 3. A boiler having an overlying fire tube portion with depending water jacketing sides and ends, having a front door and a smoke flue at one side of the rear end extending through the jacketing portions, means connecting the smoke flue with the fire tube portion and causing an endwise movement of the gases through said fire tubes, first in one direction and then in the other, and a 15 cross partition between the sides of the depending portion with an opening at the side opposite the smoke flue opening to cause a transverse movement of the hot gases from the fire box below the fire tube portion.

20 30 4. A boiler having an overlying fire tube

portion with depending water jacketing sides and ends, having a front fire door and a smoke flue at one side of the rear end extending through the jacketing portion, and a water inlet at the bottom of the rear end, 35 and a cross partition between the depending sides with an opening at the side opposite the smoke flue opening in the rear to cause a transverse movement of the hot gases from the fire box along the rear wall adjacent the 40 water inlet for the boiler.

5. A boiler comprising an overlying fire tube portion with depending water jacketing sides and ends, a cross partition between the sides with an opening at one side of the partition, the rear end having a flue opening at the opposite side of the boiler, whereby a 45 transverse movement of the products of combustion is caused in the chamber at the rear of the partition.

6. A boiler comprising an overlying fire tube portion with depending water jacketing sides and ends, a cross partition between the sides, the partition and rear end having openings therethrough at opposite sides of 50 the boiler to cause a transverse movement of the products of combustion between the partition and the said rear end.

JOHN T. BUNTING.
